United States Patent Office.

WILLIAM C. KAISER, OF LOUISVILLE, KENTUCKY.

Letters Patent No. 106,172, dated August 9, 1870.

IMPROVEMENT IN MACHINES FOR BENDING CLEVIS AND STIRRUPS.

The Schedule referred to in these Letters Patent and making part of the same.

I, WILLIAM C. KAISER, of the city of Louisville, county of Jefferson and State of Kentucky, have invented a certain new and useful Improvement in Bending-Machines for the purpose of bending plow-clevises, stirrups, chain-links, and other similar articles, of which the following is a specification.

This invention consists in the construction and arrangement of parts, as hereinafter more fully described and claimed.

The machine is composed of a cast-iron plate, to the face of which is secured the proper forms for bending any desired shape, the center form of which is secured to the plate by means of a bolt, so as to be easily changed when necessary to bend other forms, while the outside levers or forms are secured to the plate by screw-bolts through the ends, on which they are made to turn, in order to open out, and also to close up against the center form as the iron is bent.

These forms are operated by means of pins securely fastened in a side plate, immediately under the main plate, the ends of which pins are made to extend up through a slot sufficiently to enter another similar slot in the lever forms.

The last-named slots in the lever forms are cut at an angle of about thirty degrees, more or less, as the nature of the work may require it, so that, when placed in their proper position, the angle of the slots will be reversed, forming a double inclined plane or wedge, acted on by the pins of the slide-plate below, which passes up through the slot, and by means of which the forms are forced together against the iron as the slide-plate is drawn out in operating the machine, which is done by a hand-lever for that purpose.

Having thus fully explained the nature of my invention, a more minute description may be seen by reference to the drawing.

Figure 1 is a perspective view of the machine, complete.

Figure 2 is a view of the slide-plate, showing the pins and slots, and the manner of attaching it to the main plate.

A is the main plate of the machine, and is made of cast-iron.

G is the movable center form, and is secured to the plate by a bolt.

C are the outside levers or forms, which are secured to the plate A by bolts passing through the ends, on which they turn.

D are the slot-holes, forming the inclined plane by which they are operated.

E are the bolts on which the levers turn.

F are the pins of the slide-plate, by which they are operated.

H is a small pin, to be set up against the article to be bent, to keep it from bending backward in the center.

I is the lever by which it is operated.

J and K are lugs in the plate, to which the lever is attached, by the link L.

M is the slide-plate below.

N is the slot.

T is the bolt by which it is secured to the plate, and on which it slides.

F are the pins that operate the lever forms.

P is the link connecting the slide-plate M with the rock-shaft Q.

R is the lever by which the machine is operated.

I claim as my invention—

1. The combination and arrangement of the slotted clamps C, the movable center-piece G, the vertical pins F, slotted plate A, slotted and grooved sliding plate M, bolt T, connecting-rod P, transverse rock-shaft Q, having its bearings in pendants secured to the lower side of plate A, and lever R, all constructed and operating substantially as described, and for the purpose set forth.

2. In combination with the above, the clamping-device or appliance for holding in place the article while being bent, consisting of the horizontal sliding rod H, lever I, and link L, secured to the plate A by means of the lugs J K, arranged and operating as described.

WILLIAM C. KAISER.
